UNITED STATES PATENT OFFICE

EDWIN B. GILLINDER, OF PORT JERVIS, NEW YORK, ASSIGNOR TO GILLINDER BROTHERS, INC., OF PORT JERVIS, NEW YORK, A CORPORATION OF NEW YORK

DESIGN FOR A TRANSPARENT BOWL

Application filed April 21, 1928. Serial No. 26,408. Term of patent 3½ years.

To all whom it may concern:

Be it known that I, EDWIN B. GILLINDER, a citizen of the United States, and a resident of Port Jervis, county of Orange, and State of New York, have invented a new, original, and ornamental Design for Transparent Bowls, of which the following is a specification, reference being had to the accompanying drawings, forming part thereof, of which—

Figs. 1 and 2 are front and side elevations of a transparent bowl embodying my design.

Fig. 3 is a top plan view of a transparent

bowl embodying my design, showing the substantially rectangular mouth and the gently corrugated inner surface of the walls of the bowl.

Fig. 4 is a vertical central sectional view of the bowl, showing the disposition of the corrugations formed on the inner surfaces of the walls of the bowl.

I claim:

The ornamental design for a transparent bowl, as shown and described.

EDWIN B. GILLINDER.
